United States Patent Office

Des. 189,400
Patented Dec. 6, 1960

189,400

LAMP BASE

Alice G. Posey, 205 Saxon Woods Road,
White Plains, N.Y.

Filed Nov. 20, 1959, Ser. No. 58,408

Term of patent 14 years

(Cl. D48—20)

Fig. 2 is a side elevational view thereof.

Fig. 3 is a top plan view thereof with the socket and standard omitted for convenience of illustration only.

Fig. 4 is a bottom plan view thereof.

The essential features of my design reside in the portions shown in full lines.

I claim:

The ornamental design for a lamp base, substantially as shown and described.
